UNITED STATES PATENT OFFICE

158,329

RETARDER FOR BOWLING BALLS
OR THE LIKE

Nathan H. Rewalt, Muskegon, Mich., assignor to
The Brunswick-Balke-Collender Company, Chi-
cago, Ill., a corporation of Delaware

Application February 2, 1949, Serial No. 628

Term of patent 14 years

(Cl. D34—5)

To all whom it may concern:

Be it known that I, Nathan H. Rewalt, a citizen of the United States and a resident of the city of Muskegon, in the county of Muskegon, State of Michigan, have invented a new, original, and ornamental Design for a Retarder for Bowling Balls or the like, of which the following is a specification, reference being had to the accompanying drawings, forming a part thereof, in which:

Fig. 1 is a top plan view of a retarder for bowling balls or the like, showing my new design;

Fig. 2 is a side elevational view thereof; and

Fig. 3 is an end view thereof, looking at the right-hand end of Fig. 1.

The dominant features of the design are shown in full lines.

I claim:

The ornamental design for a retarder for bowl-
ing balls or the like, as shown and described.

NATHAN H. REWALT.
